CLAIM

The ornamental design for a toy basketball goal, as shown and described.

DESCRIPTION

FIG. 1 is a perspective view of a toy basketball goal showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a fragmentary left side elevational view thereof; and

FIG. 7 is a right side elevational view thereof, the left side elevational view being a mirror image except for the portion shown in FIG. 6.

FIG. 1

FIG. 3

FIG. 4

FIG. 5
